(57) **CLAIM**

I claim the ornamental design for a pliers with control key,
as shown and described.

DESCRIPTION

FIG. 1 is a top perspective view of a control key for a pliers showing our new design;

FIG. 2 is a bottom perspective view thereof;

FIG. 3 is a right side view thereof, wherein the left side view
is a mirror image thereof;

FIG. 4 is a top view thereof;

FIG. 5 is a bottom view thereof; and,

FIG. 6 is a rear view thereof.

The evenly-spaced broken lines illustrate portions of the
pliers with control key that form no part of the claimed
design. The dash-dot broken lines illustrate the boundary of
the claimed design and form no part thereof.
